RUG-EDGE-FINISHING SEAM AND
METHOD OF MAKING SAME

William J. Moran, New York, N. Y., assignor to
The Singer Manufacturing Company, Elizabeth, N. J., a corporation of New Jersey

Original application April 13, 1933, Serial No.
665,891. Divided and this application October
31, 1933, Serial No. 695,966

8 Claims. (Cl. 112—262)

This invention relates to methods of sewing and seams for sewed articles. An object of the invention is to provide an improved rug-edge-finishing seam and method of making same including a binding strip so secured to the raw edge of a rug as to conceal and protect the attaching stitches and be inconspicuous and neat in appearance and strongly resistant to deformation in use.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 of the drawings is a perspective view of a rug edge with a binding strip attached thereto in accordance with the first step of the present method. Fig. 2 is a perspective view of a rug-edge finished in accordance with the present improvement. Fig. 3 is a sectional view of the finished seam shown in Fig. 2. Fig. 4 is a plan view of the bed of a sewing machine by which the first step of the method may conveniently be carried out. Fig. 5 is a section on the line 5—5, Fig. 4, and Fig. 6 is a section on the line 6—6, Fig. 4, with the rug-edge and binding strip in their relative positions for attachment together by the laterally vibrating needle of the machine.

This application is a division of my copending application, Serial No. 665,891; filed Apr. 13, 1933.

While the method may be performed entirely by hand it is more convenient to initially attach the binding strip 1 to the raw edge 2' of the loosely woven rug base 2 by use of a conventional zigzag overedge lock-stitch sewing machine having the usual reciprocatory and laterally vibratory needle 3 and a flat bed 4 upon which is mounted the thick work-supporting plate 5 slotted at 6 to receive the fastening screws 7 which are threaded into the bed 4 and permit the plate 5 to be adjusted laterally of the line of seam formation. The plate 5 is undercut to provide a rug-pile clearance recess 8 above which is the relatively thin edge 9 spaced from the bed 4 and having its front corner rounded at 10. The work is fed through the machine preferably by means of a toothed top-feeding wheel 11, Fig. 6.

Cooperating with the edge 9 of the rug-supporting plate 5 is the rug-edge-bending guide 12 having a shank 12' received in a groove 13 in

the plate 14 secured to the bed 4 by screws 15 passing through slots 16 in the plate 14. The shank 12' of the guide 12 is held in the groove 13 by means of the screw 16 which is carried by the strap 17 overlying the shank 12' and screwed to the plate 14. Provision is thus had for adjustment of the guide 12 transversely of the line of seam-formation to cause the needle 3 to penetrate the downwardly bent edge of the rug at the desired distance from the edge at each alternate thrust. The lateral adjustment of the guide 12 is preferably so made that the needle on its work-penetrative thrust along the line a—a, Fig. 6, will emerge at the juncture 18 of the pile fibres 19 of the rug with the woven rug base 2 at the raw edge of the latter. The needle, on its next or overedge descent passes along the line b—b, Fig. 6, without penetrating any part of the work. The zone between the lines a—a and b—b represents the stitching zone within which the bent over edge-portion of the rug is disposed.

The guide 12 has an upstanding guide-wall 20 which is preferably slightly concaved and which cooperates with the overhanging edge 9 of the plate 5 to bend downwardly the raw edge of the rug and present it in this condition to the laterally vibrating needle 3. The guide 12 is cut away at 21 to admit the needle, as shown best in Fig. 5. It also has a confining wall 22 overhanging the undercut edge 9 and merging into the upstanding wall 20.

Let into the bed 4 is the throat-plate 23, Fig. 4, formed with the laterally elongated needle-aperture 24 and depending needle-guide fin 25. The throat-plate 23, which is generally oval in shape, is cut away at 26, 27 to admit the flat strip-guide tube 28 which is received in a groove 29 cut in the bed 4 lengthwise of the line of seam-formation. The strip-guide 28 terminates closely in front of the needle-hole 24 in the throat-plate and the edge 27 of the throat-plate is slanted upwardly and rearwardly, as shown in Fig. 5, to smoothly guide the binding strip 1 issuing from the guide-tube onto the throat-plate. The guide-tube 28 has secured thereto a flat shank 30 which is slotted at 31 for reception of the fastening screws 32. The groove 29 in the bed 4 is wider than the guide-tube 28, thus permitting the guide-tube to be adjusted sidewise or transversely of the line of seam-formation, so that one edge of the binding strip 1 will underlap the downturned raw edge of the rug, Fig. 6, and be safely caught by the needle 3 on its work-penetrating thrust and stitched in juxtaposition with the raw edge of the rug by a series of zigzag overedge lock-stitches; the plane

of the binding strip being horizontal and at an angle to the substantially vertical plane of the base 2 of the rug at the raw edge of the latter. The plate 5 is recessed in its under face at 5' to afford clearance for the binding strip 1 after it passes the needle 3.

Fig. 1 illustrates the work after it has passed through the machine. The binding strip 1 is first attached to the raw edge of the rug by a series of overedge zigzag lock-stitches comprising the needle-thread loops 33 and shuttle-thread 34. It will be observed that the work-penetrating stitches have a relatively wide bite in the relatively loosely woven base 2 of the rug and a relatively narrow bite in the selvage of the more tightly woven binding strip 1. The overedge stitches in conjunction with the work-penetrating stitches, bind the fibers of the rug-base tightly together and effect a more secure anchorage of the work-penetrating stitches in the rug-base and a more secure attachment of the initially stitched edge of the binding strip to the raw edge of the rug.

After the binding strip 1 has been attached to the rug-edge, as shown in Fig. 1, it is folded around the overseamed edge into engagement with the back of the rug and whip-stitched at 35 by hand to the back of the rug; the binding strip 1 concealing and protecting the raw edge of the rug, as well as the zigzag stitches, and projecting but little beyond the edge of the pile-forming portion 19 of the rug.

Having thus set forth the nature of the invention, what I claim herein is:—

1. In a rug-edge-finishing seam, a rug body comprising a woven base having a face and back with pile-fibres attached to said base and projecting from the face side of the latter, said base having a raw edge, a binding strip having an edge-portion in juxtaposition with said raw edge but at an angle to the plane of the back of the rug-base, a series of overedge stitches embracing and covering said juxtaposed edge-portions exclusive of the projecting ends of said pile-fibres, said binding strip being folded around its overseamed edge into engagement with the back of the rug, and means for securing said binding strip to the back of the rug.

2. In a rug-edge-finishing seam, a rug-body comprising a woven base having a face and back with pile-fibres attached to said base and projecting from the face side of the latter, said base having a raw edge, a binding strip having an edge-portion in juxtaposition with said raw edge but at an angle to the plane of the back of the rug-base, a series of zigzag lock-stitches embracing and covering said juxtaposed edge-portions exclusive of the projecting ends of said pile-fibres, said binding strip being folded around its overseamed edge into engagement with the back of the rug, and means for securing said binding strip to the back of the rug.

3. An edge-finishing seam for sewed articles comprising a woven pile-fabric presenting a pile face, a back face and a raw edge, a binding strip having an edge in juxtaposition with said raw edge of the pile-fabric, a series of overedge stitches

anchored in the juxtaposed edges of said pile-fabric and binding strip and enclosing both of said edges exclusive of the projecting ends of pile-fibres of the pile-fabric, said binding strip being folded about the overseamed edges of the pile-fabric and binding strip into engagement with the back face of the pile-fabric, and means for securing the binding strip to the back face of the pile-fabric.

4. The construction set forth in claim 3 with the overedge stitches more deeply anchored in the edge of the pile-fabric at the back face of the latter than at the pile face thereof.

5. In a rug-edge-finishing seam, a rug-body comprising a woven base having a face and back with pile-fibres secured to said base and projecting from the face of the latter, said base having a raw edge-portion, a binding strip having an edge-portion in juxtaposition with said raw edge-portion but at an angle to the plane of the back of the rug-base, a series of overedge stitches embracing and covering said juxtaposed edge-portions exclusive of the projecting ends of said pile-fibres, said series of stitches having a relatively wide bite in the base of the rug and a relatively narrow bite in the binding strip, said binding strip being folded around its overseamed edge into engagement with the back of the rug, and means for securing said binding strip to the back of the rug.

6. The method of binding the margin of a body-material comprising anchoring one edge of a binding strip to the body-material margin by a stitching thread passed diagonally through the body-material from points on one face of the body material relatively widely spaced from the edge thereof to points on the other face of the body-material relatively narrowly spaced from the edge thereof and through one edge-portion of the binding strip, folding the binding strip around the edge of the body-material, and securing the binding strip to the first mentioned face of the body-material.

7. The method of binding the raw edge of a rug of pile-fabric which consists in simultaneously presenting the rug-edge and an underlapping binding strip to an overedge sewing machine having a reciprocatory straight needle, with the rug face down and with its raw edge-portion bent downwardly so as to be inclined to the plane of the binding strip within the stitching zone, and in folding the unattached portion of the binding strip around the stitched portion and securing it to the back of the rug.

8. The method of binding the raw edge of a rug of pile-fabric which consists in simultaneously presenting the rug-edge and an underlapping binding strip to the reciprocatory and laterally vibratory needle of a zigzag-stitch sewing machine, with the rug face down and with its raw edge-portion bent downwardly so as to be inclined to the needle-path and to the underlapping binding strip, and in folding the unattached portion of the binding strip around the stitched portion and securing it to the back of the rug.

WILLIAM J. MORAN.
